UNITED STATES PATENT OFFICE.

MARCUS JOSIAH BARTLETT, OF CHICAGO, ILLINOIS, ASSIGNOR TO JOSEPH SILVERMAN, OF CHICAGO, ILLINOIS.

WIRE-ROD-BENDING MACHINE.

No. 898,424.

Specification of Letters Patent.

Patented Sept. 15, 1908.

Application filed July 18, 1907. Serial No. 384,453.

To all whom it may concern:

Be it known that I, MARCUS JOSIAH BARTLETT, a citizen of the United States, and a resident of Chicago, in the county of Cook and State of Illinois, have invented certain new and useful Improvements in Wire-Rod-Bending Machines; and I do hereby declare that the following is a full, clear, and exact description thereof, reference being had to the accompanying drawings, and to the figures and letters of reference marked thereon, which form a part of this specification.

This invention relates to improvements in machines for bending or giving shape to wires or rods to form parts or members of wire furniture, as twisted rod chairs, tables and the like, and the invention consists in the matters hereinafter set forth and more particularly pointed out in the appended claims.

Among the principal objects of my invention is to provide an improved mechanism for forming eyes on the ends of rods shaped to produce members for making wire furniture, or for other purpose.

A further object of my invention is to provide an improved machine for bending or shaping a wire or rod to constitute a chair back member.

As shown in the drawings:—Figure 1 is a plan view of the machine embodying my invention. Fig. 2 is a similar view of the parts shown in different positions. Fig. 3 is a front elevation thereof. Fig. 4 is a longitudinal, vertical section taken on line 4—4 of Fig. 1. Fig. 5 is a section taken on line 5—5 of Fig. 3. Fig. 6 is a vertical section taken on line 6—6 of Fig. 3. Fig. 7 is a detail horizontal section taken on line 7—7 of Fig. 3. Fig. 8 is a detail horizontal section taken on line 8—8 of Fig. 3. Fig. 9 illustrates a lever and its mounting which co-operates with one of the wire bending forms. Fig. 10 is a fragmentary perspective view of a portion of said lever. Fig. 11 is a section taken on line 11—11 of Fig. 9. Fig. 12 is a detail of the jointed end of the lever shown in Fig. 9. Fig. 13 is a perspective view of two of the bending forms removed from the machine. Fig. 14 is a detail section taken on line 14—14 of Fig. 1. Fig. 15 is a perspective view of a lever for operating one of the principal forms of the machine. Fig. 16 is a horizontal section taken on line 16—16 of Fig. 6. Fig. 17 illustrates one of the halves or members of a chair back which the ma-

chine is designed to form. Fig. 18 is a top plan view of a leg twisting machine, showing my improved eye forming mechanism attached thereto.

The chair back member which my machine is designed to produce is shown in Fig. 17 and consists of a single piece of wire rod formed to provide a straight side *a*, a long curved portion *b*, a straight portion *c*, a shorter curved portion *d*, a straight oblique portion *e*, a shorter straight portion *f*, a curved portion *g*, and a terminal eye *h*. The particular shape of the member herein shown is used in making the chair back shown in my U. S. Design Letters Patent Number 38,279, dated October 9, 1906.

Referring now to the construction of the machine, 20 designates, as a whole, the main or supporting frame of the machine supported on legs or standards 21, and 22 designates a horizontal work table supported on or constituting the upper part of an auxiliary frame 23 mounted on the main frame.

25 designates a form mounted above the work table 22 and pivoted thereto by means of a stud 26 (Figs. 1, 2 and 14). Said form is provided with a curved margin 27 about which one end of the rod is bent or curved.

28 designates a stationary form fixed to the upper face of the work table in advance of the form 25 and provided with a curved edge 29 and a straight edge 30 about which the rod is bent.

31 designates a third form mounted on a body or shank 35 which is pivoted to its support to swing the form 31 towards and away from the work table. Said form 31 is provided with a curved margin 32 about which a part of the rod is bent or curved. Between the latter form 31 and the form 28 is located 95 a short grooved form block 34 having a short straight groove to give form to a portion of the rod, and constituting also part of a clamping device to hold the rod fixed in place.

36 designates, as a whole, an eye-forming mechanism which forms the eye at the end of the rod after the same has been bent to shape.

In the operation of forming or bending a rod into the shape shown in Fig. 17, a straight wire rod is inserted into the machine between the pivoted end of the form 25 and the curved margin of the stationary form 28, and said rod extends at its advance end into engagement with a stop 40 carried by the end of an oblique arm 41 extending from the ma-

chine. The said rod is engaged at a point adjacent to the pivoted end of the form 25 by the sharpened end of a pivoted holding pawl 43 which prevents endwise withdrawal of the rod. Thereafter the rear or free end of the rod is grasped by the hand and is bent about the curved margin 27 of the form 25 to the position indicated in dotted lines in Fig. 1 and full lines in Fig. 2, thus forming the 10 curved portion *b* and the straight portion *a* of the chair back member. The partially formed rod is locked in this position by means of a swinging latch 45 hinged to the form 25 and adapted to swing downwardly into engagement with the rod lying against the curved margin 27 of said form. The form 25 is prevented from swinging inwardly during this operation by means of a latch 46 hinged to the free end thereof and adapted to bear 15 against the end margin of the work table 22, as best shown in Figs. 1, 2 and 4.

The next part of the bending operation consists in bending the advance end of the wire rod about the curved margin 29 of the 20 stationary form 28 and against its straight margin 30 thereof, into the position indicated in dotted lines in Fig. 1 and in full lines in Fig. 2, thus forming the shorter curved part *d* of said member and the straight oblique portion *e* thereof. This is effected by 25 means of a lever 50 carrying a bearing roller 51 which latter is adapted, when the parts are in position for producing this bend, to lie on the side of the straight rod remote from the curved portion 29 of the form 28, as shown in 30 Figs. 1 and 4; and said lever and the rollers carried thereby are thereafter swung horizontally on a vertical axis concentric with said curved margin 29, the roller 51 pressing 35 and curving the rod against the said curved margin 29 of said form 28. Said lever 50 and the manner of carrying the roller thereby is specially constructed to permit both the lever and the part carrying the roller to 40 be swung upwardly out of the way of the other operative parts of the machine in the position shown in Fig. 9. Said parts are made as follows, reference being made to 45 Figs. 4, 9, 10, 11 and 12: 52 designates a rotative pivot block for the lever; provided 50 with a sleeve or hub 53 which extends downwardly through openings in the form 28 and the work table 22 and has rotative bearing 55 therein. It is secured in place by a nut 54. The lever is provided with two fork arms 55, 55 which fit on opposite sides of said block and are apertured to receive a pivot pin 56 extending through said block. The block is provided on its upper face with an upwardly 60 opening groove or notch 57 adapted to receive an arm 58 which carries the roller 51, said arm being pivoted in the rear end of the groove by a pivot pin 59. The said roller arm occupies said groove when in its operative position, as shown in Fig. 4. The fork

arms 55 of said lever 50 are provided at their upper sides with inwardly extending flanges 60, 60, herein shown as formed on angle pieces 61 that are attached to the outer faces of said form arms, and the downwardly facing surfaces of said flanges are adapted for engagement with the square sides or faces of lugs 62, 62 formed on the opposite side faces of the roller arm 58. The pivot block and its hub is made hollow and receives the upper end of a spring-pressed rod 63. Said rod 63 is pressed upwardly by means of a spiral contractile spring 64 attached to the lower end of the rod and to a part 65 depending from the work table 22. The said upper end of the spring-pressed rod is pointed as shown and engages a notch 66 in the lower margin of the roller arm 58. When the parts are in the position shown in Fig. 4, the engagement of the lugs 62 with the flanges 60 of the lever arms holds the roller arm in alinement and rigid with the lever 50 so that at this time there is no danger of the lever arm swinging upwardly when the rod is formed around the margin 29 of the stationary form 28. When 70 said parts are not used it is desired to throw the same upwardly in the position shown in Fig. 9. To do this, the lever 50 is first thrown upwardly, to swing the flanges 60 away from the lugs 62, after which the roller arm is free to be swung upwardly to the position shown in Fig. 9. As the roller arm swings upwardly another pair of the side faces of the lugs 62 engage with the flanges 60. At this time the spring 64 acts through 75 the rod 63 to hold the roller arm upwardly and the engagement of the flanges 60 with the lugs 62 acts to hold the lever in its upper position. 80

The grooved form 34 stands normally 85 above the level of the work table, but must be depressed to permit the rod, as it is swung against the straight side 30 of the form 28, to engage the same. The notched form is pivotally mounted so that it may be brought 90 parallel with the straight side of the form 28, and is thereafter swung partially round to bend the part *f* of the chair back member at an angle to the part *e*. 95

The grooved form 34 is formed on the upper end of a shank 70 (Figs. 3 and 13) provided at its sides with apertured lugs 71, 71 adapted to engage with a vertical pin 72 fixed in the auxiliary frame, the parts being 100 so arranged that the pin 72 constitutes a vertical guide for said form and a hinge about which the form swings. The construction associated with said grooved form whereby 105 it is lowered to receive the rod as the latter is bent around the stationary form is made 110 as follows: The slotted form 34 is held normally in its uppermost position through the medium of a hinged cam lever 80 which engages a bearing block 81 on which the lower 115 end of the shank of the form rests, said block 120

having guiding engagement with the frame 20 by means of vertical parallel pins 82 engaging suitable guide openings in said frame. The end of said cam lever 80 is hinged to a vertically reciprocating link 83 which latter is loosely connected at its lower end with a vertically swinging treadle bar 84 which is hinged to a horizontal rod 85 extending between the legs of the frame. The said link 19 and the treadle bar is held normally in its uppermost position by means of a spiral contractile spring 86 attached at its upper and lower ends to pins or lugs on said link and machine frame, respectively (Figs. 3 and 5). When the treadle bar 84 is depressed, therefore, it lowers the link 83 and thereby swings the cam 80 into a position to permit the grooved form to drop by gravity flush with the upper face of the work table. 20 Thereafter the rod is swung over the depressed grooved form, as indicated by the dotted line position in Fig. 1. Thereupon the treadle bar 84 is released and the spring 86 returns the link 83 to its uppermost position and acts through the cam 80 to raise the grooved form to the position shown in Fig. 3. In order to hold the rod being bent in said grooved form, a short bar 90 is attached to the work table and projects over one end of 25 said grooved form in a manner to permit the rod to pass thereunder when the form is depressed, but prevents the rod rising from the grooved form after the latter has been raised. After the rod is thus engaged with the 30 grooved form, said form is swung inwardly towards the work table about its hinge pin 72 to the position shown in Fig. 2 to produce the short straight bend f. This is effected through the medium of a lever bar 92 which 35 is adapted to be inserted into a suitable opening in the outer face of the shank of said grooved form, said bar being preferably removable in order that the same may be moved out of the way of the operator when 40 not in use. The treadle bar 84 may be locked in its lower position to hold the grooved form 34 depressed by means of an arm 93 extending laterally from a standard 94 rising from the machine base at one side of 45 said treadle bar; said treadle bar being connected with the pivot shaft or rod 85 by a joint permitting of sufficient lateral play of the treadle bar to allow said bar to be shifted beneath and away from said arm 93. A 50 stop arm 94^a at the top of said standard 94 limits the upward movement of the treadle bar and its link under the action of the spring 86. Thereafter the form 31 is swung inwardly to produce the bend or curve g in 55 the back member. The shank or body 35 of said form 31 is shown as hinged to the shank of the form 34 by means of a hinge pin 95 extending through overlapping lugs 96, 97 on the shanks or bodies of said forms. The 60 shank or body of the form 31 is provided

with an opening 98, as shown in Fig. 13, that is adapted to receive an operating bar 99 for swinging the same inwardly.

When the form 31 swings inwardly to produce the bend g the end of the wire rod is 70 swung into position for engagement with the eye forming mechanism which constitutes an important feature of my invention and which will now be described, reference being made more particularly to Figs. 1, 2, 3, 4, 6 75 and 8.

100 designates a horizontal rotative disk that is mounted between the work table 22 and a plate 101 of a bracket 102 beneath the rear end of the work table. Said disk is provided on its upper face with a centrally located circular lug or projection 103 that extends upwardly through a slot 104 in the work table. The disk is also provided on its lower side with a hub 105 which extends downwardly through a slot 106 in the lower bracket plate 101, said slot 106 being parallel with and beneath the slot 104. Non-rotatively fixed to said hub below the plate 101 is a ratchet wheel 107 adapted to be engaged by a spring-pressed pawl 108 carried by a lever 109 having a flattened inner bearing end 110 that is rotatively mounted on the hub below said ratchet wheel. Said ratchet wheel and the bearing end of the lever are fixed to the hub by means of a collar 111 that is removably attached to the lower end of the hub, as by the set screw shown in Fig. 4.

112 designates a vertically movable pin 100 that extends upwardly through an opening in the disk 100 and its hub, with its upper end normally above the upper face of the central projection 103 of the disk. The lower end of said pin carries a head 113 which 105 rests on a vertically swinging lever arm 114 that is pivoted at 115 to the machine frame. Said lever arm 114 is adapted to be lowered through the medium of a link 116 pivoted at its upper end to the lever arm and at its lower end to a treadle bar 117 (Figs. 6 and 16). The lever arm 114 is normally held in its uppermost position to project the upper end of the pin 112 above the disk 100 through the medium of a spiral contractile spring 119 110 which is fixed at its lower end to a lug 120 on the treadle bar link and at its upper end to the machine frame in the manner shown in Fig. 3. A stop 122 fixed to the machine frame engages the lever arm 114 to limit the 115 upward movement of the lever 114. When said lever arm is depressed the weight of the head at the lower end of the center pin 112 serves to lower the latter so that the free end of the rod at the terminal of its newly formed curved portions g may pass thereover. In order to prevent the center pin 112 from shifting off the lever bar 114 when said pin is at its lowermost position, I have provided a retaining device 123 consisting of a forked 120 125 130

arm which is attached to the upper side of the lever arm 114 in position for the arms thereof to pass on either side of said pin when the lever is in its lowermost position, thus 5 holding the latter stable.

The disk 100 is provided with an eccentric lug 125 against which the free end of the wire rod strikes when moved over the disk by the action of the swinging form 31. When the 10 center pin 112 is thereafter raised in rear of the said terminal end of the rod said rod is confined between the center pin and the eccentric lug 125. It will be noted that the eccentric lug 125 is formed to provide adjacent 15 to the center pin a sharp biting edge. When the end of the wire is thus confined between said eccentric lug and center pin, the disk is turned in the direction indicated by the arrow in Figs. 1 and 2 through the medium of 20 the pawl and ratchet mechanism described. By reason of the biting engagement of the biting edge of said eccentric lug with the end of the wire rod, the rotation of the disk in this manner serves to curve the end of said 25 wire in the form of an eye. Inasmuch as the parts of the rod which have been bent in the manner hereinbefore described are at this time firmly held engaged with the different forms, the said rod is immovable endwise so that 30 the eye forming mechanism described, comprising the disk 100, centering pin 112 and eccentric lug 125 travels along or toward the rod during the formation of the eye, such movement of the mechanism being permitted 35 by reason of the presence of the slots 104, 106. This operation of the eye forming mechanism is shown more plainly in Fig. 18, wherein the machine is shown adapted for forming the eyes on the ends of the members 40 of a twisted leg, one of the eye-forming mechanisms of that machine being shown in the position which it assumes after the eye has been completed and the other mechanism being shown in the position it occupies 45 before the formation of the eye is begun.

The eye-forming disk and parts associated therewith are returned to normal positions after the eye has been formed and the back member removed by devices made as follows: 50 130 designates a horizontally and longitudinally reciprocating guide bar that engages suitable guides in the auxiliary frame in the manner best shown in Figs. 4, 6 and 8. Said guide bar is provided with a laterally and inwardly directed arm 131 that engages the periphery of the disk 100 on the inner side thereof. 132 designates a spiral contractile spring that is attached at one end to a pin 133 fixed to the auxiliary frame and at its 55 other end to a pin 134 which extends through a slot 135 in the side member of said frame and is fixed to the inner end of the guide bar. The eye forming mechanism is thus moved against the action of the spring 132, and the 60 power stored in said spring has the effect, 65

when the formed rod is lifted from the machine, to return the traveling eye forming mechanism to its outermost or normal position.

140 designates a swinging gage bar (Figs. 1 and 2) that is located in position to arrest the eccentric lug 125 of the eye forming disk at the proper place to adjust it for engagement by the end of the rod on which the next eye is to be formed. When said eye forming 75 mechanism is returned by the spring 132, the disk is rotated by the handle 109 or otherwise until one of the flat faces of the lug 125 is brought up against the gage bar which properly gages or places said lug. The said 80 gage bar is spring pressed against a suitable stop 141 to hold it in position for its end to extend across the disk while permitting the end of the bar to swing outwardly so as to allow the lug 125 to rotate past the same. A 85 spring 142 holds the gage bar normally against said stop.

It is desired that the treadle bar 117 be locked in its lowermost position when it is swung downwardly to permit the center pin 90 of the eye forming mechanism to drop in order that said pin will remain in its lowermost position while the end of the wire rod is being swung over the disk against the eccentric lug 125. This may be effected by mechanism herein shown made as follows: 145 designates a standard rising from the base of the machine at the side of the treadle bar 117 and is provided with a lug 146 which extends laterally towards said treadle bar. The pivotal connection of the treadle bar with the shaft 85 is sufficiently loose to permit the treadle bar when depressed below said lug 146 to be shifted inwardly beneath the same, thereby holding the treadle bar downwardly against the action of the spring 119. As herein shown, means are provided for automatically releasing the treadle bar and permitting the center pin of the eye forming mechanism to move upwardly under the action of said spring 119 just after the end of the wire rod has passed over the eye forming disk into contact with the eccentric lug 125. This result is effected in the present instance by devices made as follows: 148 designates a 115 vertical rock shaft that has bearing at its lower end in the lateral arm 146 of said standard 145 and an upper arm 149 thereof, and has bearing at its upper end in a sleeve 150 formed on the auxiliary frame, as shown 120 in Fig. 6. The said vertical rock shaft 148 is provided at its lower end with a cam piece 151 which is adapted, upon rotation of the rod in the proper direction, to be swung 125 against the treadle bar 117 and disengage the same from the lug 146. The means for rocking said shaft 148 to produce this result consists of a crank arm 152 at the upper end of the shaft (Figs. 1 and 7) which is adapted for engagement by the body or shank of the 130

swinging form 31 as the latter is swung inwardly.

After the eye has been formed in the end of the rod, in the manner described, the form 25 is swung on its pivot lugs 26 from the position indicated in full lines in Figs. 1 and 2 to that indicated in dotted lines in Fig. 2 to complete the chair back member. This is conveniently effected by means of a lever 160, shown in place in Fig. 2, and shown removed from the machine in Fig. 15. This lever is preferably arranged to be removed from the form when not in use so that it will be out of the way of the operator. It is provided at one end with a hand grip 161 and at its other end with a short laterally directed rigid arm 162. Said arm is provided on its upper face with a short pin or lug 163 that is adapted to engage with an oblique notch 164 on a plate or bar 165 fixed to the upper face of said swinging form 25. The said plate or bar 165 is separated from the swinging form 25 at its free or unattached end so as to permit the inner end of said lever 160 and its arm 162 to pass between the plate and bar, as indicated in dotted lines in Fig. 2. The free end of said arm carries a roller 166 that extends beneath the plane of the lower face of said arm and is adapted, when the lever is fixed to said swinging form in the manner described, to engage a part of the rod which lies against the margin 27 of said swinging form. The lever 160 is locked to said swinging form by means of a latch 167 which is pivoted between its ends 35 to said lever by means of a horizontal pivot pin 168. The latch is provided at its inner end with a flat horizontal portion 169 provided with an aperture 170 which is designed for engagement with a stud 171 projecting upwardly from the upper face of the swinging form 25. The said latch is provided at its outer end with a flat portion 172 between which and a part of the lever is interposed a spiral expansively acting spring 173, said 40 spring serving to hold the latch engaged with the stud 171. When the lever is thus engaged with the swinging form 25 (Fig. 2) it constitutes means whereby the swinging form may be swung from the full line position shown in Fig. 2 to the dotted line position shown in said figure, the latch 46 being released to permit the form to thus swing from one position to the other. After said form has thus been swung into this position 45 and carries the straight portion *a* of the back member into the position indicated in dotted lines in Fig. 2, the said back member is finished and is ready to be removed from the machine. Before said back member is removed from the machine, the lever 160 is detached from the swinging form 25 and the lever 50 and the roller bearing arm 58 carried thereby are raised into the position shown in Fig. 9. Thereafter the grooved form 34 is 50 depressed, after which the back member may

be shifted rearwardly to disengage the same from the various parts of the machine. In order to positively disengage said grooved form 34 from the formed back member, the treadle bar link 83 is provided at its upper end with a forwardly extending lug 180 (Fig. 3) that is adapted for engagement, when the treadle bar 84 is depressed to its lowermost position, with an offset arm 181 fixed to the shank or body of the grooved form and thus pull said form downwardly. The said arm 181 is continued on the side of the shank of the grooved form remote from the link 83 and is provided at its end with an adjustable stop screw 182 which engages a stationary part of the machine when the said form member is swung into position to bring the groove parallel with the straight portion 30 of the stationary form and thus constituting a stop to arrest said grooved form in this position. 55

In Fig. 18 of the drawing I have shown my improved eye forming mechanism as made a part of a machine for forming the twisted legs of chairs, tables and the like. In said figure said eye forming mechanism is designated as a whole by 36 and is the same construction as the eye forming mechanism hereinbefore described. In this construction two eye forming mechanisms are shown for forming eyes on both end members of the twisted rod leg, both of said eyes being formed while the leg occupies a single fixed position, and after the members have been twisted together. Said machine embraces as the main parts thereon, a frame 190 provided with a suitable work table 191 on which are mounted the supports 192, 192 for the two eye forming mechanisms. 193 designates a twisting head for twisting the loop of the wire from which the twisted leg is formed, 100 said twisting head being operated from any suitable source of power. 194 designates a clamp for holding said wires in their parallel positions between which clamp and the twisting head the wires are twisted together. 105 195, 195 designate stationary forms located between said clamp 194 and the eye forming mechanism outwardly against which the ends of the wires, in which are formed the eyes, are curved or bent in diverging relation preparatory to the eye forming operation. 110

An important feature of my improved machine lies in the eye forming mechanism so constructed and arranged that an eye may be formed in the end of a rod at a time when the rod is being held rigid from endwise movement. This is made possible by reason of the fact that the eye forming mechanism is movable along the length of the wire rod during the formation of the eye, thus rendering it unnecessary that the rod shall move towards the eye at this time. This feature of my invention is capable of use whenever it is desired to form an eye at the end of a rod while it is held in a fixed position. A further ad- 115 120 125 130

vantage of this feature of the invention in a machine of this kind is that a chair or other furniture member may be finished on the machine, thus avoiding the trouble and expense of changing the piece from one machine to another to completely form or bend the same. It becomes practicable, therefore, to do the work much more rapidly and accurately than if two or more machines be employed for accomplishing the different parts of the work.

A machine organized in the same general manner as that herein illustrated may be employed for forming furniture members and like pieces somewhat different from that herein shown and I do not wish to be limited to the structural details illustrated except as herein made the subject of specific claims.

I claim as my invention:

1. In a wire rod bending machine, means for holding a rod in fixed position, and mechanism for forming an eye on the end of the rod when so held, said mechanism being movable along the length of the rod during the formation of the eye.

2. In a wire rod bending machine, means for holding a rod in fixed position, and an eye forming mechanism comprising a part engaging the end of the rod, said part being rotative on its axis and movable along the length of the wire.

3. In a wire rod bending machine, means for holding a rod in fixed position and an eye-forming mechanism comprising a rotative part provided with a center pin and with an eccentric lug between which the rod is held, said part being movable along the length of the wire, for the purpose set forth.

4. In a wire rod bending machine, means for holding a rod in fixed position, and an eye-forming mechanism comprising a rotative part provided with a center pin and with an eccentric lug between which the rod is held, and means whereby said pin is movable to lower it below the upper face of said rotative part, said part being movable along the length of the wire, for the purpose set forth.

5. In a wire rod bending machine, means for holding a rod in fixed position, and an eye-forming mechanism comprising a rotative disk, a support therefor which is slotted to permit the disk to move endwise of the rod, means for rotating the disk, a vertically movable center pin extending upwardly through an opening in said disk, an eccentric lug rising from the disk between which and the raised center pin the end of the rod is held, and means for normally holding the pin with its end raised above said disk constructed to permit the pin to drop with its upper end below said disk.

6. In a wire rod bending machine, means for holding a rod in fixed position, and an eye forming mechanism comprising a rotative part provided with a center pin and with an

eccentric lug between which the rod is held, said eccentric lug being provided with a biting edge adapted to engage the rod, and means whereby said rotative part is movable along the length of the wire.

7. In a wire rod bending machine, means for holding a rod in fixed position, and an eye forming mechanism comprising a rotative disk provided with means for engaging the end of the rod, pawl and ratchet mechanism for rotating the disk, and means whereby said disk is movable along the length of the wire during its rotation.

8. In a wire rod bending machine, means for holding a rod in fixed position, and an eye forming mechanism comprising a rotative disk provided with means to engage the end of the rod, and a guide for the disk arranged to permit the disk to move lengthwise of the rod during rotation of the disk.

9. In a wire rod bending machine, means for holding a rod in fixed position, and an eye forming mechanism embracing a rotative part provided with means to engage the end of the rod, a slotted support for said rotative part arranged to permit said part to move endwise of the rod, and means for rotating said part.

10. In a wire rod bending machine, means for holding a rod in fixed position, and an eye forming mechanism comprising a rotative disk, a support therefor which is slotted to permit the disk to move endwise of the rod, a hub on said disk, a ratchet wheel fixed to said hub, a lever having bearing on said hub and carrying a pawl which engages the ratchet wheel for rotating the disk, said disk being provided in its upper face with means for engaging and holding the end of said rod.

11. In a wire rod bending machine, means for holding a rod in fixed position, and an eye forming mechanism comprising a rotative disk, a supporting frame slotted to permit the disk to move endwise of the rod, a vertically movable center pin normally projecting above the face of the disk, an eccentric lug on said disk between which and the center pin the end of the rod is held, means for rotating said disk, and a gage for adjusting the position of said eccentric lug.

12. In a wire rod bending machine, means for holding a rod in fixed position, and an eye forming mechanism comprising a rotative disk, a supporting frame slotted to permit the disk to move endwise of the rod, a vertically movable center pin normally projecting above the face of the disk, an eccentric lug on said disk between which and the center pin the end of the rod is held, means for rotating said disk, and a swinging gage bar projecting over said disk into the path of said eccentric lug, for the purpose set forth.

13. In a wire rod bending machine, means for holding a rod in fixed position, and an eye forming mechanism comprising a rotative

disk provided on its upper face with means for engaging the rod, constructed upon rotation of the disk to form the eye, means whereby said disk is moved along the length of the rod during the rotation of the disk, and means for restoring the disk to its normal position.

14. In a wire rod bending machine, means for holding a rod in fixed position, and an eye forming mechanism comprising a rotative disk provided on its upper face with means for engaging the rod, constructed upon rotation of the disk to form the eye, means whereby said disk is moved along the length of the rod during the rotation of the disk, and automatic means for restoring the disk to its outer position.

15. In a wire rod bending machine, means for holding a rod in fixed position, and an eye forming mechanism comprising a rotative disk provided on its upper surface with a concentric and an eccentric projection between which the end of the rod is held, means for rotating the disk, a slotted support for the disk permitting the disk to move endwise of the rod during the rotation thereof, and a spring against the action of which the disk is moved along the length of the rod, said spring acting to restore the disk to its normal position.

16. An eye forming mechanism comprising a rotative disk provided on its upper face with means for holding the end of a rod, a support therefor and means for rotating the disk, and guiding connections between the disk and support arranged to permit the disk to be moved lengthwise of the rod during rotation of the disk.

17. An eye forming mechanism comprising a rotative disk, means for rotating the disk, a support therefor, guiding connections between the disk and support arranged to permit the disk to be moved along the length of the rod during the rotation of the disk, a pin extending from the disk centrally thereof, and a concentric lug extending from said disk between which and the pin the end of the rod is held.

18. An eye forming mechanism comprising a rotative disk, means for rotating the disk, a support therefor, guiding connections between the disk and support arranged to permit the disk to be moved along the length of the rod during the rotation of the disk, a pin extending from the disk centrally thereof, and a concentric lug extending from said disk between which and the pin the end of the rod is held, the center pin being movable to shift the same out of the plane of the face of the disk.

19. An eye forming mechanism comprising a rotative disk, a support therefor, slotted connections between the disk and support permitting the disk to be moved along the length of the rod, means on the upper face of the disk for engaging the end of the rod to

hold the same, and pawl and ratchet mechanism for rotating said disk.

20. A machine for making wire rod furniture members and the like from wire rods and forming an eye thereon, comprising stationary and movable forms about which the rod is bent to a desired shape, and mechanism for forming an eye on the end of said member, said eye-forming mechanism being movable along the length of the rod member.

21. In a machine for forming furniture members or the like from straight wire rods, comprising a swinging form having a curved surface about which a portion of the rod is bent, a stationary form having a curved and straight surface about which another part of the rod is bent, means for forming the rod about the curved and straight surface of the stationary form, a swinging form located at the advance end of the straight surface of said stationary form and provided with an upwardly opening groove to receive the rod intermediate part of its length, and a swinging form located in advance of the grooved form and provided with a curved surface adapted to bend the end of the rod in curved form.

22. In a machine for forming furniture members or the like from straight wire rods, comprising a swinging form having a curved surface about which a portion of the rod is bent, a stationary form having a curved and straight surface about which another part of the rod is bent, means for forming the rod about the curved and straight surface of the stationary form, a swinging form located at the advance end of the straight surface of said stationary form and provided with an upwardly opening groove to receive the rod intermediate part of its length, a swinging form located in advance of the grooved form and provided with a curved surface adapted to bend the end of the rod in curved form, and an eye-forming mechanism located in advance of the latter swinging form to form an eye in said rod member.

23. A machine for making furniture members and the like from a continuous wire rod, comprising a work table, a form pivotally mounted thereon and provided with a curved surface about which one end of the wire is formed, a latch engaging the rod to lock it to said curved surface of the form, an operating lever provided at its end with a lug adapted to engage a notch in a part carried by said form, and a latch carried by the lever adapted to engage a lug carried by the form at a distance from said notched part, whereby the lever is detachably fixed to the form, and other wire bending forms located on said table in advance of said pivoted form for giving shape to the other end of said wire rod.

24. In a machine for making furniture members and the like from continuous wire rods, the combination with a work table, of a

stationary form having curved and straight surfaces, and a lever swinging on an axis concentric with said curved surface of the stationary form for forming the wire rod about 5 said curved and straight surfaces of said form, and forms for finishing the bending of the latter end of the rod.

25. In a machine for making furniture members and the like from continuous wire rods, the combination with a work table, of a 10 stationary form having curved and straight surfaces, and a lever swinging on an axis concentric with said curved surface of the stationary form for forming the wire rod about 15 said curved and straight surfaces of said form, and forms for finishing the bending of the latter end of the rod, said swinging lever being provided with a roller which engages the rod to form the same about the curved 20 surface of said stationary form, said lever and the part carrying the roller being jointed to permit the roller and the lever to be swung upwardly as and for the purpose set forth.

26. In a machine for forming furniture members and the like from continuous wire rods, the combination with a work table, of a 25 curved form about which one end of the rod is bent, a stationary form provided with a curved and a straight surface about which 30 the other end of the rod is bent, and a swinging grooved form adapted to receive said lat-

ter end of the wire and to bend a portion of said latter end of the wire at an angle to the part which is formed against the straight portion of the stationary form, said grooved form being vertically movable for the purpose set forth. 35

27. In a machine for forming furniture members and the like from continuous wire rods, the combination with a work table, of a 40 curved form about which one end of the rod is bent, a stationary form provided with a curved and a straight surface about which the other end of the rod is bent, a swinging grooved form adapted to receive said latter 45 end of the wire and to bend a portion of said latter end of the wire at an angle to the part which is formed against the straight portion of the stationary form, said grooved form being vertically movable, and a part overhanging said grooved form for holding the rod engaged with said form while permitting the rod to pass thereunder for engagement with said grooved form. 50

In testimony, that I claim the foregoing as 55 my invention I affix my signature in the presence of two witnesses, this 26th day of June A. D. 1907.

MARCUS JOSIAH BARTLETT.
